Primary Examiner — Khawaja Anwar*Assistant Examiner* — Julice Seung Eun Oum(74) *Attorney, Agent, or Firm* — Haynes and Boone, LLP(57) **CLAIM**

We claim the ornamental design for a leg press exercise machine, as shown and described.

DESCRIPTION

FIG. 1 is a front, side perspective view of a leg press exercise machine of a fitness equipment unit;

FIG. 2 is a front view of the leg press exercise machine of FIG. 1;

FIG. 3 is a rear view of the leg press exercise machine of FIG. 1;

FIG. 4 is a first side view of the leg press exercise machine of FIG. 1;

FIG. 5 a second side view of the leg press exercise machine of FIG. 1;

FIG. 6 is a top view of the leg press exercise machine of FIG. 1; and,

FIG. 7 is a bottom view of the leg press exercise machine of FIG. 1.

The broken lines and the dot dash lines shown throughout the figure views form no part of the claimed design.
